[57] CLAIM

The ornamental design for a lighted walking cane, as shown.

DESCRIPTION

FIG. 1 is a perspective view of the lighted walking cane of my new design;

FIG. 2 is a left side elevational view of the lighted walking cane of my new design; it being understood that the right side elevational view is identical thereto;

FIG. 3 is a rear elevational view of the lighted walking cane of my new design;

FIG. 4 is a front elevational view of the lighted walking cane of my new design;

FIG. 5 is a top plan view of the lighted walking cane of my new design; and,

FIG. 6 is a bottom plan view of the lighted walking cane of my new design.
